UNITED STATES PATENT OFFICE.

JOHN B. WALKER, OF BIRMINGHAM, ALABAMA.

METHOD FOR MAKING INGOT-MOLDS AND LIKE TUBULAR CASTINGS.

1,262,719.

Specification of Letters Patent. Patented Apr. 16, 1918.

Application filed August 25, 1917. Serial No. 188,167.

To all whom it may concern:

Be it known that I, JOHN B. WALKER, a citizen of the United States of America, residing at Birmingham, in the county of 5 Jefferson and State of Alabama, have invented certain new and useful Improvements in Methods for Making Ingot-Molds and like Tubular Castings, of which the following is a specification.

10 My invention relates to the art of making sand molds and cores for use in casting ingot molds, pipe and like tubular castings, and this application forms a continuation in part of the application filed by me on 15 the 12th day of March, 1917, Serial No. 154,402.

On object of my present invention is to devise a simple process for forming in one operation, preferably by the use of a jarring table or jolt machine, both the green sand core and cheek of the mold, thus simultaneously producing the whole mold and greatly simplifying and cheapening the cost of mold production and at the same 25 time obtaining a standard of uniformity in the packing of both cheek and core sand not otherwise obtainable.

A further feature of my invention is the novel process for drawing the pattern so 30 as to avoid all delicate operations, use being made of a crane or hoist means to successively and freely strip the cheek from the pattern and the pattern from the core. It is essential to this feature of my invention 35 that the pattern become expansible, as soon as the cheek is stripped therefrom, to avoid injury to the core as it is drawn therefrom.

Where the cheek and core are simultaneously formed on a sectional tubular pattern, it is essential to devise some simple and effective method of holding the pattern sections closed and I have conceived the idea of accomplishing this by means forming 40 a part of, or at least adapted to be stripped with, the cheek, my preferred method being to provide an encircling band of sand which surrounds and, as it is rammed, compresses the pattern sections so as 45 to hold them in closed position, after which the ramming of both core and cheek can proceed in due course. The advantage of such a method hardly needs comment for the stripping of the cheek will obviously free the 50 pattern to expand when it is stripped from the core.

When a jarring process is used to ram the sand core and cheek about an ingot mold pattern, I have heretofore found it necessary to ram by hand the sand under 60 the outstanding lug patterns. According to my present invention I avoid this objectionable operation by leaving the pattern free of any outstanding projection which will interfere not only with the vertical stripping of the cheek but also with the jolt ramming of sand thereunder and I provide detachable lug patterns which are free to slide vertically in guides on the main pattern, the molds for the lugs being formed 65 by the use of these detachable patterns by either of the two following methods, to-wit: Ramming the cheek and then removing sufficient of the rammed sand to form a seat into which the lug pattern can be dropped 70 in its guides and afterward packing sand by hand around the pattern; or, mounting the lug patterns on the main pattern before the ramming of the cheek is completed so that the lug patterns will be jolted down 75 during the last stage of the ramming operation and will thus settle with the sand which will be found to be rammed hard and firm under the lug pattern.

As illustrative of an apparatus for carrying the methods forming the subject matter of my present invention into effect, reference is made to the accompanying drawings, in which:—

Figure 1 is a vertical sectional view 90 taken on the line 1—1 of Fig. 5, showing the core and cheek both rammed and illustrating the two methods of forming the lug mold with detachable patterns.

Fig. 2 is a side elevation of Fig. 1 with the 95 flask and pattern broken away to illustrate the sand band formed for holding the pattern contracted during the ramming operation.

Fig. 3 is a detail view illustrating the 100 means for limiting the expanding movement of the pattern.

Fig. 4 is a view corresponding to Fig. 1 showing the mold closed and ready for the pouring operation.

Fig. 5 is a plan view of Fig. 1 showing 105 both lug patterns in place in the completed sand mold.

Similar reference numerals refer to similar parts throughout the drawings.

In carrying my method into effect I prefer to use a jarring table or jolt machine 110 1 on

22
which is seated a removable stool drag 2 to which the center column 3 of the collapsible core arbor is secured by a wedge 4. The arbor comprises four staves 5 seated to rock in 5 sockets on the drag and carrying at their upper ends pawls 6 which are adapted to be engaged and forced outwardly to expand the core arbor by means of a wedge plate 7 bearing on the pawls and a wedge key 8 driven 10 through the top of the column and bearing on the plate. Co-acting lugs 9 and 10 on the column and staves limit the outward movement of the latter, all as is more fully described in my Letters Patent No. 1,221,116.
15 The stool is recessed in its upper face at 11 to form the drag portion of the mold. I first mount a stripping plate 12 on the drag and detachably connect it to the flask, when the latter is lowered onto it, by clamps 13
20 adapted at their lower ends to be received in notches 14 in the drag. I next lower the tubular pattern 15 over the arbor, its lower end being seated on the drag sand and loosely centered by the stripping plate. The
25 pattern, which forms the subject matter of my application above referred to, is split across corners into vertical half sections pivotally connected at their upper ends by the lugs 16 and pivot pins 17. In the abutting
30 faces of the joints between the pattern sections I provide suitable means on each side to guide them together and hold them against relative movement when collapsed, such means comprising upper dowel pins 18
35 with suitable sockets therefor and lower hook lugs 19 adapted to work in recesses 20 and by engagement with stop plates 21 to limit the expansion of the pattern. The pattern is lowered into place by a tackle connected to hanger plates 22 connected to the
40 pivot pin 17, thus leaving the pattern sections free to swing to closed position. I next lower the flask 23 over the pattern onto the stripping plate and connect it by clamps
45 13 to the stripping plate and by clamps 24 to the stool drag. The flask also is formed in vertical sections as described in my Letters Patent No. 1,221,117, the sections of
50 which are normally held closed by clamps 25 engaging flanges 26 along the meeting edges of the flask sections. When the apparatus is thus assembled sand is first introduced between the pattern and the flask to a height of about a foot, the jarring table is
55 then operated to give the apparatus three or four jolts. As this sand which forms an encircling sand band about the pattern is packed it acts to force together the lower or free ends of the sectional pattern and prevent them from spreading. Having thus
60 preliminarily secured the pattern in position, sand is filled in on both the inside and outside of the pattern to build up the cheek and core simultaneously and substantially
65 evenly, the jolting operation proceeding

until the sand is packed practically to the top level of the pattern.

It will be observed that the pattern does not carry lugs for forming the ears or lugs on the ingot mold and my reason for leaving 70 the exterior of the pattern free of projections will be apparent when it is considered that my purpose is to pack the sand by the jolting or jarring process. If the lugs were formed on the pattern it would be practically impossible to mechanically accomplish 75 the proper packing of the sand under the lugs. According to my present process, the operator uses a shovel, the blade of which is shaped so that, when thrust downwardly 80 into the packed sand around the top of the pattern, it will remove sufficient of the sand to form a seat which will receive a detached lug pattern 27. To insure the lug patterns being set in the right position, they are provided with tongues 28 that fit into vertical 85 guide slots 29 in the pattern. After seating the lug patterns, additional sand is thrown over them and rammed. If desired, after sand has been rammed slightly above the 90 bottom of the slots 29, the lug patterns may be set in their vertical guide slots 29 and enough sand thrown in to hold them in position while the ramming proceeds, the patterns being preferably disposed so that they 95 will settle slightly during this ramming operation to make sure that the sand under them is rammed tightly.

When the ramming operation has been completed, the clamps 24 are knocked loose 100 and the crane is first applied, in the manner described in my Letters Patent No. 1,221,117, to lift the flask and strip the cheek from the pattern and stool drag and deliver it to foundry pits for finishing. The lug patterns will strip off with the cheek and can readily be drawn as part of the finishing operation. The crane hooks are then applied to the hanger plates 22 of the pattern and, the encircling sand band which forms part 110 of the cheek having been removed, the bottom end of the pattern is released to expand to the full extent permitted by the stop lugs 19. As the pattern is lifted to strip it from the core, it will ride freely up the core and the latter will be thus protected from collapse or injury. As soon as the pattern clears the core it can be set over another core arbor and the operation repeated, it being noted that the pattern sections will 115 swing together into closed position by gravity as soon as they are free of the core.

By the method suggested of forming the sand band for contracting the pattern I save one operation required to contract and secure the pattern sections together and another operation to release them so that the pattern can expand. It will be understood however that the sand band is only the preferred means, as my invention contemplates 125 130

the use of any device or means which will hold the pattern contracted during the ramming operation and which will strip with the cheek. In order to facilitate the strip-

5 ping of the cheek, the pattern is preferably formed with a slight taper upwardly and this taper is effective within the pattern also to facilitate its stripping from the core.

After the cheek and core have been dried 10 and packed the flask is lifted and set back over the core, the stripping plate having been removed and the mold is then closed, as shown in Fig. 4, ready for pouring operation.

15 Having thus described my invention, what I claim as new and desire to secure by Letters Patent, is:—

1. The herein-described process for simultaneously ramming a sand mold and core 20 for hollow articles by the use of a tubular sectional pattern which is expansible, which consists in first ramming an encircling sand band about the lower end of the sectional pattern to hold it contracted before ramming sand within the pattern, as and for 25 the purposes described.

2. A process for making cheeks and cores simultaneously with a common sectional expansible pattern, which consists in ramming 30 a sand band forming part of the cheek to hold the pattern sections in contracted relationship before starting the ramming of the core.

3. A process for making mold cheeks and 35 cores simultaneously with a sectional expansible pattern, which consists in first ramming a sand band about the bottom end of the pattern to contract it and hold it contracted and then proceeding substantially 40 evenly with the jolt ramming of the sand both within and without the pattern to contemporaneously produce a cheek and core of substantially equal density, substantially as described.

4. A method of making molds and core 45 simultaneously with a sectional expansible pattern, which consists in first packing a sand band about the bottom end of the pattern to contract it and hold it contracted

50 and then proceeding with the packing of the sand both within and without the pattern, and stripping the mold with said sand band as a part thereof from about the pattern before stripping the pattern from the 55 core.

5. The herein-described method of making sand molds for ingot molds on a jarring table, which consists in first packing the sand about the pattern by jolting to form 60 the mold, removing sufficient of the packed sand at the top of the mold to form seats to snugly receive lug patterns, inserting the

lug patterns in the seats thus formed, and ramming sand about the lug patterns to complete the operation, substantially as de- 65 scribed.

6. The herein-described method of making sand molds for ingot molds on a jarring table, which consists in first jolt ramming the cheek about an ingot mold pattern with 70 the mold lug patterns removed, removing sufficient of the packed sand at the top of the cheek to form seats to snugly receive the lug patterns, inserting the lug patterns in the seats thus formed, ramming sand 75 about the lug patterns to complete the operation, stripping the cheek with the lug patterns therein upwardly from the pattern, and drawing the lug patterns from the cheek before finishing it, substantially as 80 described.

7. A process for the production of sand molds for casting ingot molds and the like, which consists in assembling the flask pattern and core arbor on the drag, simultaneously ramming the cheek, core and drag about the same pattern, stripping first the cheek from the pattern and then the pattern from the core and drag without removing the core from the drag, and remounting the 90 cheek on the drag surrounding the core preparatory to casting.

8. A process for the production of sand molds for casting ingot molds and the like, which consists in jolt ramming both cheek 95 and core simultaneously on the drag using the same pattern, first stripping the cheek from the pattern, then stripping the pattern from the core, and finally reassembling the cheek on the drag about the core for the 100 casting operation.

9. A process for the production of sand molds for casting ingot molds and the like, which consists in jolt ramming the cheek, core and drag simultaneously on the same 105 pattern, leaving the core mounted on the drag, stripping the cheek vertically from the pattern, stripping the pattern vertically from the core, and replacing the cheek on the drag about the core to close the mold 110 ready for pouring.

10. A process for the production of sand molds for casting ingot molds and the like, which consists in simultaneously jolt ramming both cheek and core on a common expansible tubular pattern and introducing the sand so as to start the cheek first and afterward to build up the core and cheek substantially evenly during the jolt ramming operation. 115

In testimony whereof I affix my signature.

JOHN B. WALKER.
